UNITED STATES PATENT OFFICE

2,362,429

PIVOT STRUCTURE

Alva G. Blanchard, Shreveport, La.

Original application October 14, 1935, Serial No. 44,988, now Patent No. 2,233,395, dated March 4, 1941. Divided and this application March 6, 1940, Serial No. 322,625

3 Claims. (Cl. 287—1)

The invention relates to the structure of a valve operating device.

While the device is capable of general application I have illustrated it particularly in connection with the operation of valves in outlets from steam boilers. It is sometimes desirable to provide a plurality of steam outlets from the boiler through which steam may be directed to operate regulators, fuel or water valves, and the like. Such a construction is usually operated in response to the level of the water in the boiler and my device is so illustrated.

It is an object of the present invention to provide means in connection with a single lever to operate a plurality of valves at different stages relative to the height of the water in the boiler.

It is desired that the valves be opened in a predetermined sequence so that the steam may be allowed to pass through one line first and then through other lines in a predetermined sequence.

The invention also involves a structure which is strong and compact and easily assembled in position.

The invention further involves the structure of the valve operating means through which the valve operating pin is held in position with a minimum amount of labor and expense.

The invention will be better understood in connection with the description of the drawing here-with in which

Fig. 1 is a vertical section through a valve assembly shown as connected with the float operated lever.

Fig. 2 is a horizontal section through the assembly disclosed in Fig. 1, the float being omitted.

Fig. 3 is a transverse detail of the yoke showing the manner in which the valve operating pin is secured in position.

Fig. 4 is a view similar to Fig. 3 showing the manner in which the pin may be removed when desired.

The present application is a division of my co-pending application Serial No. 44,988, filed October 14, 1935, for Safety appliance for boilers, now Patent No. 2,233,395, March 4, 1941.

In carrying out my invention I contemplate forming in the wall 1 of the steam boiler an opening 2 formed to receive a collar 3 adapted to be welded in position in said opening, as shown at 4. The collar 3 is threaded at its outer end at 5 to receive a plug 6.

The plug 6 is formed to screw within the opening in the collar 3 and to provide outlets there-through for the steam from the boiler. There

may be two or more of these openings and in the present embodiment I have shown three outlet passages through the plug, said outlets 7, 8 and 9 having at their outer ends steam conducting pipes 10, 11 and 12, respectively. It will be understood that said pipes may conduct the steam to any steam operated device.

At the inner ends of the passages 7, 8 and 9 are inserted valve seats 13. Each valve seat is adapted 10 to cooperate with an adjacent valve, the valves 14, 15 and 16 cooperating with the outlets 7, 8 and 9, respectively. Each valve has a rearwardly extending valve stem 17 with an opening therein to receive a cross pin 18 mounted within a yoke 19 on the valve operating lever 20. In order that the valves may be operated in a predetermined sequence the openings through which the cross pin 18 passes are of different lengths in the different valve stems. I have shown the stem of the 15 valve 16 as providing a close fit about the pin 18. In the stem of the valve 15, however, the opening is elongated, as shown at 21, and the opening in the stem of the valve 14 is elongated still more, as shown at 22. It will be obvious 20 from this construction that when the lever is operated to move the valves the valve 16 will be moved first and at a predetermined interval thereafter the valve 15 will be opened and at a still later interval the valve 14 will open.

25 The lever 20, which is employed to operate the valves has at its end adjacent the valve a yoke 23. The lower end of the yoke engages with a pivot pin 24 which forms a fulcrum for the lever and allows the swinging of the lever in a vertical plane. At a point above the fulcrum 24 the cross pin 25 is mounted so as to engage through the openings in the valve stem as previously described. Between adjacent stems I provide spacers 26 which assist in maintaining the valves 30 spaced equally along the pin 18.

With reference to Figs. 3 and 4, I have shown how the pin 18 may be secured in position in the yoke of the lever with a minimum consumption of time and labor. The yoke 19 is formed with an opening 27 at one side and on the opposite side there is a recess or counterbore 28 which extends only part way through the wall of the yoke. At the end of the recess, however, there is a small opening 29 through which a punch 30 may be inserted to drive the pin from its mounting. In order to hold the pin in position with one end in the recess 28 I upset the metal about the opening 27 with a chisel or other instrument 31 so that it will prevent longitudinal movement of the pin from its seat. It will be obvious, however,

that this upset projection shown at 32 may be driven from its position holding the pin in place by the punch 30 when it is desired to remove the pin.

The lever 20 is operated by a float 33 in the present embodiment, said float having a connection at 34 with the end of the lever.

In the operation of my device it will be obvious that the valves will be opened in response to pre-determined levels of the water in the boiler. When the water is above a certain level all of the valves will be closed, but as the level is depressed first one will open and then the next, and finally the third. It will be seen, however, that if the level of the water is not lowered beyond a certain point all of the valves need not open, but each valve will open when the proper level of the float in the boiler is reached.

My invention is exceedingly simple. It will be obvious that the plug 6, upon which the valve structure is mounted, is one unitary device and that the removal of the plug will allow access to all of the valves in an obvious manner. The device is simple and strong in construction and will not easily get out of order or fail to function.

I claim:

1. In a device of the class described, the combination comprising a yoke, a pivot pin, an opening in one side of the yoke to receive said pivot pin, a second opening in the other side of said yoke in alignment with said first mentioned opening, said second opening including a stop shoulder adapted to receive the end of said pivot

pin whereby the axial position of the pin within the yoke is determined, said pin terminating within said first mentioned opening when the other end of the pin is in engagement against said stop shoulder, and a portion of the wall of the yoke about the first mentioned opening being upset toward the pin to hold the pin in place.

5 2. In a device of the class described, the combination comprising a lever having a U-shaped yoke on one end thereof, aligned openings in the arms of said yoke, the opening in one of said arms including a stop shoulder of substantially the same diameter as the other opening in the other arm, a pivot pin fitting within and terminating in 10 such other opening and having its opposite end in engagement against said stop shoulder, and an upset projection on the inner peripheral wall of such other opening and extending into the path of the pin so that the pin is held in place but is 15 releasable under pressure applied through the stop shouldered opening against the end of the pin therein.

20 3. In a device of the class described, the combination comprising a yoke including spaced arms, 25 an opening in one arm of the yoke, an opening in the other arm of said yoke arranged in alignment with said first opening, a pivot pin disposed in said openings and spanning the yoke, said pin terminating within said openings and a portion 30 of the wall of one of said arms being upset inward toward the pin to hold the pin in position.

ALVA G. BLANCHARD.
